CLAIM

The ornamental design for a functional trainer exercise machine, as shown and described in the accompanying figures.

DESCRIPTION

FIG. 1 is an isometric, right-front view of a functional trainer exercise machine;

FIG. 2 is an isometric, right-rear view of a functional trainer exercise machine;

FIG. 3 is a front side view of a functional trainer exercise machine;

FIG. 4 is a right side view of a functional trainer exercise machine;

FIG. 5 is a back side view of a functional trainer exercise machine;

FIG. 6 is a top side view of a functional trainer exercise machine; and,

FIG. 7 is a bottom side view of a functional trainer exercise machine.

The broken lines in FIGS. 1 through 7 represent unclaimed environmental subject matter and form no part of the claimed design.

1 Claim, 7 Drawing Sheets
